UNITED STATES PATENT OFFICE

2,028,774

AUTOMATIC CULTIVATOR

George Hantjopoulos, New York, N. Y.

Application March 26, 1935, Serial No. 13,039

20 Claims. (Cl. 97—36)

The purpose of this invention is to provide a cultivator adapted to be operated and steered by hand for cultivating a garden, vegetables, vineyards or between rows of corn, cotton, tobacco and for other similar purposes.

This machine cultivates by cutting the soil, slice by slice, in a rapid way, chopping all roots of the weeds in its path and freeing the plants from weeds.

The machine consists of a case enclosing rotary and operating mechanism, with the front end mounted on traction wheels and with hoes mounted at the rear, which may readily be raised or lowered and steered at will by a handle which is affixed to the top of the case. The case is provided at the front with an extension upon which an engine is mounted for self propelling.

Other features and advantages of the invention will appear from the following description, taken in connection with the drawings, wherein:

Figure 1 is a view showing a longitudinal section through the case showing the operating mechanism of the interior thereof.

Figure 2 is a sectional plan through the case on line 2—2 with parts omitted, and with part thereof showing the upper drive shaft with the other parts at the rear shown below.

Figure 3 is a plan view of the machine with parts omitted.

Figure 4 is a side elevation of the machine.

Figure 5 is a detail showing a section through the differential and showing openings through which set screws may be reached for holding the inner differential gears on the shaft.

Figure 6 is a view showing an end elevation of the rear of the machine, with parts omitted.

Figure 7 is a cross section on line 7—7 of Figure 1.

Figure 8 is a cross section on line 8—8 of Figure 1.

Figure 9 is a plan view of an internal yoke in which the hoe shafts are mounted and by which the relative positions thereof may be adjusted.

Figure 10 is a cross section through the yoke on line 10—10 of Figure 9.

Figure 11 is also a cross section through the yoke on line 11—11 of Figure 9.

Figure 12 is a side view of the yoke shown in Figure 9.

Figure 13 is a cross section through the special clutch arrangement on the upper drive shaft.

Figure 14 is a cross section on line 14—14 of Figure 13.

Figure 15 is a diagrammatic view showing the path of travel of the holes in fine lines for one

position and in dotted lines for another position.

In the drawings the cultivator is shown as it may be made wherein numeral 1 indicates the case forming a housing for the mechanical parts, numeral 2 the hoes, and numeral 3 a representation of an engine by which the device may be operated.

The case 1 is preferably made as shown with a forward section 4, a rear section 5, and a relatively narrow intermediate section 6. This case is supported upon traction wheels 7 and 8 at the front and rests upon a third wheel 9 at the rear. The upper side of the case is provided with a handle 10 by which the device may be held by hand, and the motor 3 is placed on a platform 11 at the front which is resiliently mounted upon arms 12 and 13 by springs 14 and 15.

The motor 3 may be of any type or design, and may be operated by gasoline, oil, or any fuel, or an electric motor may be used if desired. This motor is connected through a universal coupling 16 to a shaft 17, and the shaft is mounted in bearings 18 and 19 with a thrust bearing 20 in the bearing 19. The thrust bearing is formed in a bushing 21 which is threaded into the bearing 19, and the interior of the bushing is provided with an opening into which the end of the shaft 17 may extend as shown. The shaft 17 is provided with a worm 22 which meshes with a worm gear 23 on a transverse shaft 24 upon which it is fixedly mounted, or keyed as shown and a spiral gear 25 is also fixedly mounted on the shaft 24 and this meshes with a spiral gear 26 on a shaft 27 which drives a differential 28 of the traction wheels.

The differential 28 is positioned about a shaft 29 which is formed in two sections with one section extending from each side of the differential. The gear 26 runs free on the shaft; however it is provided with a toothed hub 30 at one side which engages a sliding collar 31 that is keyed to the shaft, as indicated by the dotted lines 32, and when it is desired to drive the device by the motor the collar 31 is thrown into engagement so that the gears 23 and 26 are in mesh and will rotate the shaft, and thereby rotate the differential gears.

The differential is driven by a gear 33 on the shaft 27 which meshes with a large gear 34 attached to the internal housing 35, and this housing is provided with the small idler pinions 36 which mesh with the differential gears 37 and 38 on the respective sections of the front axle or shaft 29. The gears 37 and 38 are fixedly attached to the ends of the sections of the axle 55

by set screws 39 and 40, and as it is substantially impossible to reach these set screws, openings 41 and 42 have been provided through the gear 34, and the housing 35, so that a screw driver 5 may be placed through these parts to reach the set screws, or other holding means for these gears on the respective sections of the axle. The traction wheels 7 and 8 may be of any type or design, and may be mounted upon the axle in 10 any manner. It is preferred to use wheels with projections 43, or other gripping means, on their outer surfaces as shown.

The sliding collar 31 is operated by a yoke 44 on the end of an arm 45 and the arm is pivotally mounted in a bearing 46 on the inside of the case as shown. The upper end 47 of the arm 45 is pivotally attached to a link 48 at the point 49 and the link is pivotally attached to the lower end of a lever 50 at the point 51. The lever 50 extends upward through the plate 52 forming a cover for the housing, and is pivotally mounted on a pin 53. The lever 50 is also provided with a spring pin 54 which is operated by a handle 55 attached to the upper end of the lever, and this 20 engages a segment 56 provided with notches 57. The pin 54 is resiliently held downward by a spring 58 as shown in Figures 1 and 4; however it will be understood that this lever may be formed in any manner, or the lever 50 may be held in different positions by any means.

The shaft 24 upon which the gear 23 is mounted is rotatably mounted in bearings 59 and 60 having bushings 61 and 62 therein which are similar to the bushing 21, and these are also provided with balls 63 forming thrust bearings at the ends of the shaft. The lower part 64 of the section 4 of the case 1 is provided with an opening 65 having a cover plate 66 held by screws 67 in order to provide clearance for the gear 34 in assembling the differential in the case. It will be understood, however, that this is only a typical arrangement as the case may be made of any other design or arranged in any other manner in order to facilitate assembling.

The shaft 17 is also provided with a gear 68 which is keyed to the shaft and this gear meshes with a gear 69 on a shaft 70 which is the upper drive shaft and extends through the central portion 6 of the case, and this shaft drives the whole 40 operating mechanism at the opposite end of the case. The gear 69 is freely mounted upon the shaft 70 as shown in Figure 13 and is formed with a hub 71 which extends outward from each side and recesses are formed therein. The end surface of the hub at one end is provided with teeth corresponding with similar teeth on the sliding collar 72 which is slidable on a bushing 73 and the bushing and collar are keyed to the shaft 70 by key 74 which extends through the shaft and also through the bushing 73 and into notches in the collar 72. The bushing 73 is provided with slotted openings permitting a sliding movement therein in relation to the key. The member 72 is operated by a yoke 75 which is connected to the lower end of a lever 76 as shown in Figure 1 and the lever 76 is pivotally mounted in the case on a pin 77. The upper portion of the lever is provided with a ratchet similar to the ratchet on lever 50 and adapted 50 to hold the lever in different positions in the same manner. At the inner end of the bushing 73 is a comparatively thick flange or disc 78 which is positioned to frictionally engage the face of the gear 69 and on the opposite side of the gear 68 is a similar disc 79 which is keyed to the shaft

10 by a key 80, and it will be noted that with the member 73 released by member 72 a spring 81 will force the member 78 against the gear 69 and thereby clamp the gear between the members 78 and 79 so that the gear will be frictionally held to the shaft and adapted to rotate therewith, and when it is desired to release the gear the member 72 is drawn backward by the yoke through the lever 76 until it engages a nut 82 threaded on the bushing 73 so that the spring 10 will be compressed and the gear will be freed from the members 78 and 79. When it is desired to positively lock the gear on the shaft the lever 76 is moved to a further position so that the coupling members between the members 71 and 72 15 will engage and form a positive connection. The spring 81 is mounted on the shaft 70 and one end rests against a nut 83 which is threaded on the shaft 70 and the other end bears against the end of the bushing 73.

The opposite end of the shaft 70 is held in a bearing 84 which may be made as shown in Figures 1 and 2, or of any other design, and on the outer end of the shaft is a bevel gear 85 that meshes with a similar gear 86, and the gear 86 20 is mounted on a shaft 87 which is held in bearings 88 and 89 having thrust bearings similar to those formed by the bushing 21 in the bearing 19, and a sprocket 90 is also mounted on the shaft which drives a gear 91 below through a chain 92 and a sprocket 93. It will be noted that the sprocket 93 is mounted upon the hub of the gear and the gear is freely rotatable on a shaft 94 which forms the forward drive shaft for the hoes. However, this shaft is driven through a counter-shaft 95 30 and worm gears 96 and 97 as shown in Figure 8.

A rear drive shaft as hereinafter described for the hoes is also driven from the counter shaft 95 by similar worm gears, except that the gears are opposite hand so that the former and rear drive shafts are driven in opposite directions. The gear 91 meshes with a gear 98 on a small stub shaft 99, and the hub of this gear is also attached to a spur gear 100 which meshes with and drives a similar gear 101 keyed on the shaft 45 95. The shaft 99 is stationary and one end is held in a bracket 102 whereas the opposite end extends beyond the shaft 94 and is attached to a yoke 103 by screws 104 as shown in Figure 9. The worm 96 is fixedly mounted on the shaft 95 50 and this drives the worm 97 on the shaft 94 and the outer ends of the shaft 94 extend through bearings 105 and 106 in the sides of the rear section 5 of the case and on the outer ends of the shaft are eccentrics 107 and 108 which with the shaft 94 form a crankshaft for the hoes, and at the outer ends of the eccentrics are pins 109 and 110 extending from the ends thereof upon which bearings 111 are held by washers 112 and bolts 113. The bearings 111 at both sides are 60 similar and the same reference numerals are used for both.

The ends of the hoe support rods are operated through eccentrics on a shaft 114 which is driven opposite to the shaft 94 through worm gears 115 65 and 116 from the shaft 95 and bearings 117, which are mounted on the ends of the shaft 114 by crank arms 118 and 119. The worm 115 is opposite to the worm 96, and this unit also forms a crankshaft which turns in the opposite direction to the crankshaft formed by the shaft 94 and the eccentrics 107 and 108.

The shafts 94 and 114 are mounted in the yoke 103 which is shown in detail in Figures 9 to 12 and this yoke is pivoted around the shaft

94 with the outer end slideably held in the case. The outer end is provided with members 120 having curved inner surfaces 121 which ride against flanges 122 on the stationary section of the part 5 of the case, and it will be noted that with this member in the position shown in Figure 1 in which it is shown in full lines, the hoes will operate through a cycle of positions, as indicated by the lines 123 shown in Figure 15; however, 10 the rear end of this yoke may be raised until the shaft 114 is in the position shown by the dotted lines 124 which, it will be noted, will provide a different movement for the hoes as indicated by the dash lines. The outer end of the yoke may 15 be raised by raising the cap 125 forming the upper portion of the rear end of the case, and this cap is hinged at the upper end on a pin 126, and the lower end is held through a flange 127 by bolts 128. The sides of the cap 125 conform 20 to the line 129 extending from the hinge to the dotted position 124 of the shaft 114, and then downward against the outer surface of the flange 122 to the center and then outward on a line corresponding with the face of a complementary flange 130 at the end of the lower portion 5. The bolt 128 may be removed and the cap 125 raised, and then the rear end of the yoke may be raised to the position indicated by the dotted lines 124 and the cap replaced and bolted back into position. The rear end of the yoke may, therefore, 25 be raised and lowered as may be desired. The openings in the sides of the case to accommodate the ends of the yoke may be covered with cover plates, 131, which may be pivotally attached by pins 132, as shown. The rear of the case is supported upon the roller 9 which is mounted in a bracket 133 attached to the back of the case by bolts 134.

The hoes 3 are formed with plates, as shown 40 in Figures 3 and 6 having hubs 135 at their upper ends which are mounted upon rods 136, and the rods are slidably held in the bearings 111 and fixedly held in the bearings 117. The ends of these rods are formed with yokes 137, and these 45 are fixedly held in the bearings 117 by set screws 138, and it will be noted that as the shafts 94 and 114 rotate simultaneously in opposite directions, the hoes 3 will move alternately as indicated by the lines 123 in Figure 15.

The device may also be provided with a plow 50 139, as shown in Figures 1 and 3, and this may be attached to the under side of the case by bolts 140, or by any means. This device is shown in the form of a plow, however it will be understood that any means may be used in combination 55 with the device for spreading the cultivated soil around the roots of the plants.

The handle 10 may be attached to a stud 141 on the cover plate 52, as shown in Figure 1, or to the upper part of the case by any other means, and a fuel tank, as indicated by the numeral 142, may also be placed above the cover plate 52, and this may be held to the handle by a strap 143, or by any means. It will be understood, however, that any other means may be used for storing fuel, and this may be located at any point, or points, on the device.

The sides of the rear portion 5 of the case are 60 formed with openings 144, and these may be covered by cover plates 145 which may be held by bolts 146, as shown in Figures 1 and 4. Similar openings may be provided in the case at any other point, or points, and any means may be used for covering and sealing the openings. The bearings 105 and 106 are formed with the lower

sides in the lower portion of these openings, and the bearing 105 is provided with a bushing 147 which is made integral with the yoke 103, whereas the bearing 106 is provided with a similar bushing 148 that is independently mounted in the 5 bearing in the case and these bushings are held by caps 149 with bolts 150. The outer end of the yoke is provided with bushings 120 which move upward and downward with the yoke and the shaft 114 is mounted in these bushings with the 10 central part thereof held in a web 151. The outer bushing is supported by a cross member 152 from the web 151 and this is attached to a web portion 153 by upwardly extending bearings 155 and 156 at the ends thereof, and these bearings may 15 be made solid at the inner end and at the outer end provided with a cap 157 held by bolts 158 as shown in Figure 11.

It will be understood that a case or housing of any other design may be used and other changes 20 may be made in the construction without departing from the spirit of the invention.

The construction will be readily understood from the foregoing description. In use the device may be provided as shown and described, and 25 it will be noted that with an engine or motor on the forward end connected to the member 16 the device may be held and moved by the handle 10, and as the entire device is comparatively small it may be readily guided by the handle so that 30 it may be moved along a row of plants, trees, vines or the like, and the movement may be adjusted so that the hoes will penetrate a slight or considerable depth into the soil, and with the movement of the hoes also adjusted it will be possible 35 to dig weeds or cultivate, or just break the surface, or thoroughly spade or dig up a section of ground by just moving the device thereover. The device is, therefore, a power-driven, hand-operated cultivator, and as it may readily be operated 40 with very little effort, it has many uses.

Having thus fully described the invention, what I claim as new and desire to secure by Letters Patent, is:

1. A cultivator of the type having a housing 45 case with one end mounted upon traction wheels and the other resting upon a spacing roller and in which a handle is provided on the case by which the end having the roller thereon may readily be raised about the traction wheels, two sub- 50 stantially horizontal eccentric shafts extending through the case, hoes mounted on the ends of said shafts on the sides of said case and adjacent the spacing roller end and means within the case by which said hoes may be operated. 55

2. A cultivator as described in claim 1 having a motor positioned on the end adjacent the traction wheels, means whereby said motor drives said traction wheels and other means whereby said motor drives the hoe operating means. 60

3. A cultivator as described in claim 1 in which the hoes are mounted upon crank arms on the ends of the eccentric shafts extending through the casing, and on both sides thereof.

4. A cultivator as described in claim 1 having 65 means adjusting the position of one of the shafts to adjust the motion of the hoes.

5. In a hoe machine of the self-propelled type and adapted to be guided by hand, a case, traction wheels supporting one end of the case, a 70 spacing roller supporting the opposite end of the case, a handle extending upward from the case, a motor adapted to drive and operate the machine mounted on the traction wheel end of the case, spring separating said motor from the 75

mounting means, a counter shaft extending from said motor into the case, a coupling between said motor and counter shaft, a stub shaft positioned below said counter shaft, gears connecting said counter shaft to said stub shaft adapted to rotate the stub shaft from the counter shaft, a differential between said traction wheels, shafts extending from said differential to the sides of the case upon which said traction wheels are mounted, said stub shaft extending into said differential and adapted to operate the same to drive the traction wheels, a clutch on said stub shaft, means operating said clutch from the upper part of the casing, a main drive shaft positioned above the counter shaft and extending through the upper part of the casing, gears connecting the counter shaft to the main drive shaft, a clutch between said gears and the main drive shaft, a friction member within said clutch providing automatic release thereof, means operating said clutch from a point above said case, horizontal shafts positioned transversely of said case and in the end thereof opposite to that upon which the traction wheels are mounted, means driving a bushing on one of said horizontal shafts from said main shaft, an auxiliary counter shaft between said horizontal shafts, gears connecting said auxiliary counter shaft to said horizontal shafts causing rotation of said horizontal shafts in opposite directions, similar gears connecting the bushing on one of said horizontal shafts to the auxiliary counter shaft for driving the same, eccentrics on the ends of said horizontal shafts, rods mounted on the ends of said eccentrics and hoes on the forward ends of said rods.

6. A device as described in claim 5 in which one of said horizontal shafts may be raised to adjust the movement of said hoes.

7. A cultivator of the type having motor operated diggers on a case mounted on wheels and having a handle for manual operation, characterized by two horizontal shafts extending through the case, eccentric arms at each side of said case mounted on the ends of said shafts, rods pivotally mounted on the ends of said arms, diggers on the ends of said rods, and means rotating said shafts, said diggers positioned behind the main supporting wheels preventing packing of the loosened dirt by said wheels.

8. A cultivator as described in claim 7, having means rotating one of said shafts in a direction opposite to that of the other.

9. A cultivator as described in claim 7, further characterized in that the digger ends of the rods are suspended below the ends of the arms.

10. A cultivator as described in claim 7, further characterized by slidably mounting the outer ends of said rods in said arms. 5

11. A cultivator as described in claim 7, further characterized in that means is provided for adjusting the position of one of said shafts for changing the action of said hoes. 10

12. In combination with a cultivator as described in claim 7, a plow mounted on the under side of the case following the diggers for smoothing over the ground.

13. A cultivator as described in claim 7, in which traction wheels are used on the forward end and the handle is provided for raising the rear and diggers to clear rocks and the like. 15

14. A cultivator as described in claim 7, in which traction wheels are used at the forward end and the motor is mounted ahead of the traction wheels for counterbalancing the rear to facilitate raising the hoes forming the diggers. 20

15. A cultivator as described in claim 7, further characterized in that the diggers are driven through the case and the driving mechanism is enclosed therein. 25

16. A cultivator as described in claim 7, further characterized in that the diggers are driven by the motor through the case and operating levers extend above the case for manual control. 30

17. A cultivator as described in claim 7, further characterized in that the shafts are mounted in an intermediate yoke, one end of which is adapted to be raised. 35

18. A cultivator as described in claim 7, further characterized in that the shafts and gears through which one of said shafts is operated are mounted in an inner yoke. 40

19. A cultivator as described in claim 7, further characterized in that one motor operates the diggers and also the propelling means through the case in which means is provided for shifting from the diggers to the propelling means or for driving both in unison, and also in which the propelling means drives through traction wheels. 45

20. A device as described in claim 1, characterized in that the shafts are driven in opposite directions. 50

GEORGE HANTJOPOULOS.
